ATTORNEY

UNITED STATES PATENT OFFICE

WILLIAM DALES LINDSEY, OF SOUTH ORANGE, NEW JERSEY, ASSIGNOR TO GARRISON FIRE DETECTING SYSTEM INCORPORATED, OF NEW YORK, N. Y.

SPLICING AND TERMINAL DEVICE FOR FIRE DETECTING CABLES

Application filed June 11, 1927. Serial No. 198,057.

This invention relates to a splicing and connection terminal device for a fire detecting cable adapted to quickly, safely and neatly unite the ends electrically of a conducting core and a conducting insulated sleeve, respectively, the same constituting a special design of fire detecting cable. A modification thereof is adapted to unite an electrical conductor quickly, safely and neatly to the aforesaid conducting core and another electrical conductor to the aforesaid conducting insulated sleeve.

With these and other objects in view, which will become apparent as the present description proceeds, my invention consists of the novel parts and combinations of parts, all as hereinafter will be more fully described and particularly pointed out in the claims.

In a copending application for U. S. Letters Patent, filed June 11, 1927, under the Serial No. 198,056 there is disclosed an improved design of fire detecting cable adapted for use with the splicing and terminal connection devices illustrated and described in the present patent application.

Referring to the accompanying drawings forming a part of this specification in which like numerals designate like parts in all the views.

Figure 1 is a top plan view of one design of one of my special fire detecting cable splicing devices in association with a pair of cable ends, which are cut back and prepared for splicing.

Figure 2 is an enlarged section of this device in association with one of my fire detecting cable ends cut through as on the line A. B. of Figure 1.

Figure 3 is an enlarged section of this device in association with a pair of my special cable ends cut through on the line C. D. of Figure 1.

Figure 4 is a top plan view of a simplified device in association with a cable end, and two insulated wires adapted to secure electrical conductors to the core and insulated sleeve respectively of my fire detecting cable.

Figure 5 is a short length of a piece of

the fire detecting cable partly in elevation and partly in section, showing the several co-operating parts of the special cable.

Figure 6 is a vertical sectional view of the cable.

In the drawings, 10 is the outer braid of a piece of my cable; 10a is a waterproofing cover; 11 is a spirally wound strip of conducting material, brass for example; 12 is an insulating impregnated material, cotton paraffined for example; and 13 is a slotted tube of metal, soft steel for example, containing a low melting point fusible alloy 13a, an alloy of lead, tin, and bismuth for example, shown in the slot 14. 15 is an insulating member, made of moulded material, porcelain, bakelite, or vulcanite for example, provided with the hole 16, and 16' adapted to receive screws for attachment to woodwork or other building material; 17 and 17' are U-shaped aligned and substantially parallel metal clamps adapted to be securely screwed to the U-shaped metal conducting bridge 18 by the screws 20, 20, 20. The braid 10 is cut away under the clamp member 17 and 17' allowing them to make contact with the spirally wound brass conductor 11, thereby completing an electrical circuit through the conducting bridge 18.

At substantially the center of the insulating member 15 is a third metal clamping member 21, in alignment with and substantially parallel to the outer clamps 17, 17', the clamp 21 being securely screwed down to a similarly shaped metal base piece and to the insulating member 15 through the agency of the screws, 22, and 22' and adapted to unite the cores of my cable extremities, namely the slotted steel tube containing the fusible alloy. The clamp 21 and its associated metal base piece are readily seen to occupy the space between the parallelly disposed branches of the bridge 18 and spaced therefrom to avoid electrical conductivity.

Referring to Figures 2 and 3, like parts may be easily identified and their functions made clear, from the foregoing description. In Figure 4, is shown a modification of the

clamping device wherein both the slotted core and the spirally wound conductor 11 are each joined to an ordinary insulated wire such as represented at 25, 25. This form of connection is particularly useful at the limits of an electrical section subjected to fire hazards.

Referring to Figure 5, the like parts may be clearly identified and the functions of each made clear in connection with the following description. My fire detecting cable is run through a building, and is connected and spliced with the approved device herein described, and is connected with electric battery and bell, the core and sleeve respectively, to leave the circuit open so long as there is no fire and the fusible alloy remains in the slot 14 of the tube 13. With fire, however in the path of the cable, the fusible alloy melts, passes through the strands of the cotton insulating material 12, and contacts with the brass sleeve 11, thereby completing the electrical circuit through the aforesaid electric battery and bell. The insulated wires 25, and 25' in Figure 4, may conveniently and simply lead to such a battery and bell, or any other electrical alarm device, and the cable 10, may lead to any part of a building to be protected.

Having described my invention, I claim:

1. The combination with cable ends, each cable comprising an electricity-conducting core and an electricity-conducting sheath normally insulated therefrom, the cores of said cable ends being disposed in alinement in side-by-side relation immediately adjacent each other and the sheaths thereof being disposed in spaced relation, of means for electrically connecting said cores and sheaths independently of each other, said means comprising a supporting member of insulating material, spaced U-shaped clamps contacting, respectively, directly with said sheaths and carried by said supporting member, another clamp contacting directly with said cores and carried by said supporting member, the sheath openings of said spaced clamps being larger in cross-section than the core opening of said other clamp, and means constituting an electrical connection between said spaced clamps.

2. The combination with a cable comprising an electricity-conducting fusible core projecting beyond an electricity-conducting sheath normally insulated therefrom, of means for effecting independent electrical connection with said core and sheath, said means comprising a supporting member, and spaced U-shaped clamps disposed on said member in side-by-side relation, one of said clamps forming a passage for the reception of said sheath, another of said clamps forming a passage for the reception of said core, said passages being disposed substantially in alinement and the passage receiving said

core being substantially smaller in cross section than the passage receiving said sheath.

Signed at New York city in the county of New York and State of New York this seventh day of June A. D. 1927.

WILLIAM DALES LINDSEY.
